UNITED STATES PATENT OFFICE.

AUSTIN K. SPENCER AND CHARLES A. SMITH, OF GLOVERSVILLE, N. Y.

KEY-HOLE GUARD.

SPECIFICATION forming part of Letters Patent No. 352,015, dated November 2, 1886.

Application filed September 29, 1886. Serial No. 214,863. (No model.)

To all whom it may concern:

Be it known that we, AUSTIN K. SPENCER and CHARLES A. SMITH, citizens of the United States, residing at Gloversville, in the county 5 of Fulton and State of New York, have invented certain new and useful Improvements in Key-Hole Guards; and we do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 This invention relates to a key-hole guard for covering and obstructing the entrance from without to the interior mechanism of the lock through the key-hole after the key has been withdrawn from said key-hole; and the invention 20 consists, essentially, of a sliding bolt or plate located within the casing of the lock, and actuated by a two-winged tumbler and other suitable mechanism, so as to lie and be secured across the keyway intermediate between the 25 two ends thereof, and thus obstruct the entrance of a picking-tool from either direction; and it further consists in peculiarities of the construction and combination, as will be fully set forth.

In the annexed drawings, illustrating our invention, Figure 1 is an elevation of a portion 30 of the door where the lock is situated, and shows the key-hole and the handle or knob for manipulating the interior guard-bolt. Fig. 2 is a plan view of a lock-casing with the top 35 plate removed, and shows the guard in the position it occupies when the keyway is not covered. Fig. 3 is a similar view showing the guard over the keyway. Fig. 4 is a cross-section on the line 1 1 of Fig. 2. Fig. 5 is a cross-40 section on the line 2 2 of Fig. 3, and Fig. 6 is a perspective view of the guard-bolt.

Like letters indicate like parts throughout the several views.

A represents an ordinary rectangular lock-case, within which the mechanism of the lock and likewise of our improved key-hole guard 45 is situated.

B denotes the sliding guard-bolt. It is shown in an inverted position in Fig. 6 in order to expose more clearly its structural details. This 50 bolt slides upon the face a, which, when the

bolt is in proper position, will be in contact with the side of the casing, as shown in Figs. 2 and 3. The upper face, b, of the bolt is provided with a slot or depression, which receives 55 the end of a spring, C. Further, said guard-bolt is reduced in size at one end to a thin plate, c, which is slotted and provided between the slot and the extremity of the plate with a rounded projection, d. One side, also, of the 60 bolt is rabbeted at e. The guard-bolt slides upon the side of the casing, as above mentioned, and is guided in its movements by pins or projections f f' on the back plate of the casing, which pins lie one on each side of the thin 65 portion c of the bolt. The rabbeted character of one face of the bolt at e allows ample room for the lower pin, f, and permits a considerable movement of the bolt without being obstructed by said pin.

70 The bolt is actuated by means of a two-winged tumbler consisting of a spindle, g, which is journaled in the rear and top plates of the lock-casing at a point near the thin end of bolt B, and which is provided with arms or wings h h', 75 extending approximately at right angles to each other. When the spindle is rotated, the arms h h' will be brought in contact with the projection d, and thus the bolt may be pushed forward or backward. The spring C, one of 80 whose ends enters the top of the bolt B, is secured, preferably, around the posts i and j, as shown in the drawings; but other means may obviously be used to hold the end of it firm, and its function is to so act on the bolt as to 85 push it in a direction away from the key-hole. Suppose, now, the guard-bolt to be in the position shown in Fig. 2. It does not cover the keyway. The projection d is between the arms or wings h h'. Now, if the spindle g be rotated, 90 the arm h' will be caused to bear hard upon the projection d, and thus shoot the guard-bolt over into the position shown in Fig. 3, where it completely covers the keyway. In this position the arm h' will be nearly in line with the bolt, 95 and will bear upon the projection d in such a manner as to effectually lock the bolt and prevent any one from pushing it backward by the introduction of prying or picking tools into the keyway, or by other means. A lug, m, on 100 the casing serves to keep the arm h from passing beyond a certain point, and thus assists

the actuating-tumbler in maintaining its locking position. When it is desired to uncover the keyway, the spindle *g* is rotated in a reverse direction. The spring *C* will now, as soon as the bolt is relieved of the pressure of the arm *h*', drive it a short distance, or far enough to allow the arm *h* to come into contact with the projection *d*, and thus replace the bolt in the position shown in Fig. 2. Should it be desired to push the bolt still farther, the arm *h* will be allowed plenty of room in which to make the movement, for it can enter the slot in the thin part of the bolt.

In order to conveniently rotate the two-winged tumbler, we have provided a knob, *D*, which is inserted through a perforation in the door adjoining the end of the spindle *g*, and the inner end of whose shank is flattened to adapt it to enter the slotted end of said spindle *g*. This knob is supported by a perforated circular cap, *E*, through which it passes, said cap being secured to the door by screws or other convenient means. The knob and its shank are kept in place within the cap by a lug, *o*, on the shank, the perforation on the cap being indented at *o'* to allow the lug to be passed within the same.

Having thus described our invention, what we claim as new, and desire to secure by Letters Patent, is—

1. The combination of the lock-casing having lugs *f* and *f'* on the back plate and the lug *m* on one side, the bolt *B*, rabbeted at *e*, and having projection *d*, the spring *C*, the spindle *g*, journaled in the lock-casing, and having arms *h* *h'*, and the knob *D*, for rotating the spindle, all arranged substantially as shown and described. 30

2. The combination of the lock-casing having lugs *f* and *f'* on the back plate and the lug *m* on one side, the bolt *B*, having projection *d*, and rabbeted at *e*, the spring *C*, and actuating mechanism for the said bolt, substantially as described. 40

In testimony whereof we affix our signatures 45 in presence of two witnesses.

AUSTIN K. SPENCER.
CHARLES A. SMITH.
